CLAIM

The ornamental design for a child personal flotation device, as shown and described.

DESCRIPTION

FIG. 1 is a front plan view of the first embodiment of a child personal flotation device, showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a front plan view of the second embodiment of a child personal flotation device, showing our new design;

FIG. 9 is a front elevational view thereof;

FIG. 10 is a rear elevational view thereof;

FIG. 11 is left side view thereof;

FIG. 12 is a right side view thereof;

FIG. 13 is a top plan, view thereof; and,

FIG. 14 is a bottom plan view thereof.

(Continued)

The broken line in the drawings disclose unclaimed portion of the flotation device only and forms no part of the claimed design.
